UNITED STATES PATENT OFFICE

WILLIAM J. BRADDOCK AND CHARLES W. HALLER, OF WHEELING, WEST VIRGINIA,
ASSIGNORS TO WHEELING BRONZE CASTING COMPANY, A CORPORATION OF WEST
VIRGINIA

PICKLING CRATE

Application filed March 26, 1930. Serial No. 439,032.

This invention relates to a pickling crate for metallic sheets, and constitutes an improvement on the pickling crate disclosed in the patent to Charles W. Haller No. 5 1,711,054, issued April 30, 1929.

One object of the invention is to provide a crate structure of the type shown in the above mentioned patent in which the use of screw threads for maintaining the parts in 10 rigid engagement is eliminated.

Another object of the invention is to provide mutual attaching means which maintain the end and partition grids of the crate in rigidly connected spaced relation, and attach the same to the base and to the upright members serving as lifting bars, in such manner that the attaching means may be made to compensate for any tendency of the parts to work loose during continued use of 20 the crate.

Another object of the invention is to provide means for attaching a spreader to the upright members constituting lifting bars of the crate in such manner that it is firmly 25 engaged thereto by means of a connection which presents no apertures for the entrance of pickling fluid, and which is of sufficient strength and rigidity to withstand the action 30 of a pickling machine from which the crate may be suspended.

A further object of the invention is to provide a pickling crate having side and partition grids of the general arrangement of those disclosed in the above mentioned patent, 35 in which the cross sectional contour of the bars or legs constituting the grid body is such as to present to a sheet lying against the grid a surface which is relatively extended, thus avoiding injury to the sheet such as might be caused by a tendency for the sheet to flex against a relatively narrow contact line such as is presented by a bar of circular cross section.

In the accompanying drawings Fig. I is 45 a side elevation of the pickling crate; Fig. II is a horizontal sectional view taken on the line II-II of Fig. I; Fig. III is a detail plan view of the spreader constituting a member of the pickling crate; Fig. IV is a 50 detail sectional view taken on the line

IV-IV of Fig. II, showing the manner of connecting the spreader to the lifting bars of the pickling crate; Fig. V is a side elevation of one of the outer grids of the pickling 55 crate; Fig. VI is an end elevation thereof; Fig. VII is a side elevation of one of the partition grids of the pickling crate; Fig. VIII is a sectional view taken on the line VIII-VIII of Fig. VI; and Fig. IX is a 60 sectional view taken on the line IX-IX of Fig. VII.

The base 1 of the pickling crate comprises longitudinally extending bar members 2 and transversely extending bar members 3, the entire structure being integrally cast. As 65 in the structure shown in the above noted patent to Charles W. Haller, the outermost longitudinal members or sills of the base are provided with apertures 4 for receiving the lifting bars 5. Lifting bars 5 are U-shaped members, each having a horizontally extending intermediate portion 5a, and vertically 70 extending legs 5b.

It should be understood that all the members of the pickling crate are made of a copper alloy which is highly resistant to corrosion by the acid of a pickling bath. Thin edges and corners of even such an alloy, however, are attacked in time by the corrosive action of a pickling bath. Screw threads and the like are therefore to be avoided in the construction of a pickling crate. 75

While the lifting bar attachment, as shown in the above noted patent, does not require the use of screw threaded members, such as bolts and nuts, for securing the lifting bars to the base, it is further desirable that the use of such connecting members be eliminated throughout the entire crate structure. Upon the loosening of parts caused by the 85 destruction of the screw threads, it is necessary to make repairs to the crate. We, therefore, provide novel means for attaching the partition grids of the sheet pickling crate in 90 mutually spaced relation on the base 1.

Both the outer or side grids 6, and the intermediate, or partition grids 7, of the 95 crate correspond generally to the grids disclosed in the above noted patent, inasmuch as they comprise members or legs which in-

tersect to provide a reticulated structure, supporting a sheet both horizontally and vertically, while permitting free passage of the pickling fluid through the partition. In order that these grids may not present narrow contact lines to sheets lying thereagainst, and may present no points or corners which might nick or otherwise mar the sheets, we make the bars or legs 6a of the side grids, 10 and the legs 7a of the intermediate grids, of general elliptical contour in section. The major axis of the ellipse lying in the plane of extent of the grid, presents a relatively extended surface area to the sheets, while 15 avoiding the sharp edges which would be present if bars or lugs of rectangular cross sectional contour were employed. It will be noted that each of the grids constitutes a self contained and integrally cast structure, 20 having no threaded connections or other joints into which the pickling bath may enter.

The grids 6 and 7 are mounted on the base by means of longitudinally extending rods 8, which pass through aligned apertures 9 25 in brackets 10 of the side grids 6 and brackets 11 of the intermediate grids 7. The upper rods 8 also pass through matching apertures in the vertically extending legs 5b of the lifting bars 5. Lower rods 12 pass 30 through apertures 13 in lugs 14 at the lower portion of the grids 6 and 7, and pass through matching apertures in the side bars or sills 2 of the base 1. Surrounding each 35 of the rods 8 and 12 are a plurality of relatively short spacing sleeves 15, which lie between the grids, and serve to maintain them in properly spaced position, to form a plurality of sheet receiving compartments in the crate.

40 Each of the rods 8 is terminally so formed that it may not be retracted through the lifting bars 5b when it has been passed through the apertures therein. As shown, the terminal deformation to prevent retraction is effected by peening over the extending end of the rod 8 to form a clinching portion 16.

45 This method of attachment in itself does not, however, serve to initially tighten the connection between the outermost grids 6 and the lifting bars, nor between the grids 6 and 7 and their spacing sleeves 15. It also does not in itself provide means for tightening during use of the crate, if these parts should 55 work loose. For this purpose each of the two side grids 6 carries on its brackets 10 socket members 17 surrounding the apertures 9 and open on the inner side of the grid. With the rods 8 passing through the apertures 9 60 and clinched to the outer face of the lifting bars, the connection may be tightened both between the outer grid 6 and the lifting bars, and between all of the grids and their spacing sleeves, by introducing a wedge or wedges 65 into each of the sockets 17 and bearing against

the adjacent spacing sleeve. The wedging means may either be a relatively wide ledge forked to straddle the rod 8, or may be two narrow wedges inserted one on each side of the rod 8.

70 Similarly the wedge or wedges may be introduced horizontally instead of vertically as shown, if the flanges 17a, which form the socket 17 be arranged horizontally instead of vertically.

75 It will be readily understood that the relatively massive structure of the wedges is not attacked to a material extent by the relatively slow action of the pickling bath on the copper alloy of which they are formed. Also the wedges may be driven in further if the grid structure becomes loosened by slight corrosion at the ends of the spacing sleeves, and the jarring incident to the use of the sheet pickling crate with a pickling machine.

80 The arrangement in connection with the lower rods 12, which attach the grids 6 and 7 to the base 1, is generally similar. Both ends of the rods 12 projecting through apertures in the side bars or sills 2 of the base, 85 are also deformed to provide clinching portions 18 lying against the outer face of the sills 2. In this connection, however, the sills are provided with vertical slots 19 intersecting the notches 20 in which the rods 12 lie. If then a forked wedge V, or two narrow wedges, be inserted to act on both sides of the rod 12 it serves to tighten the clinched connection 90 between the grid and the sills 2 of the base.

95 Adjacent the upper ends of the lifting bars a spreader 21 is desirably attached to provide a reinforcing structure for connection of the crate as a whole to a pickling machine. The connection between the spreader and the lifting bars is also rigid and of such form that it may not be readily attacked by the pickling bath. At each corner of the spreader is a seating notch 22 for receiving a lifting bar leg, and lugs 23 turned toward each other to provide an opening for the seat of a width less than that of the lifting bar leg. Extending downwardly from the body of the spreader is a seat 24 disposed adjacent the notch 22, and having a face 100 against which the leg of the lifting bar may lie.

105 In attaching the spreader to the lifting members, the lifting bar legs 5b pass through each of the seat apertures, and the lugs are then bent over above the regions in which the spreader and the lifting bars are in contact. If desired, the lugs 23 may be peened over 110 to clinch the lifting bar legs.

115 In order to provide a rigid connection and one which is impervious to liquids, a retaining block 25 is then cast around the region of contact of each of the lifting bars with the spreader. This may be done by casting a copper alloy into a suitable mold positioned 120 in the region of the joint. When so cast, the 125

retaining block shrinks to bind the lifting bar leg and the spreader firmly together, the teat 24 assisting to anchor the block 25 in position.

5. What we claim is:

1. In a sheet pickling crate the combination of a base, a lifting bar extending upwardly from the base, a grid disposed adjacent the lifting bar, clinching means arranged to engage the grid to the lifting bar and to the base, and wedging means arranged to tighten the clinched engagement of the grid.

2. In a sheet pickling crate the combination of a base, a lifting bar extending upwardly from the base, a grid disposed adjacent the lifting bar, a rod passing through matching openings in the grid and lifting bar and terminally shaped to prevent retraction thereof, a spacing sleeve surrounding said rod, and wedging means arranged to act on said grid for maintaining said grid lifting bar and spacing sleeve in firm mutual engagement.

3. In a sheet pickling crate the combination of a base, a grid extending upwardly from the base, a rod passing through matching apertures in the grid and in the base and terminally formed to prevent retraction thereof, a spacing sleeve surrounding said rod, and wedging means arranged to act on said grid for maintaining said grid base and spacing sleeve in firm mutual engagement.

4. In a sheet pickling crate the combination of a base, spaced upright members attached to the base, a pair of upwardly extending spaced grids disposed adjacent said upright members, spacing means interposed between said grids, clinching means arranged to engage the grids to the uprights, and wedging means arranged to act on said grids to maintain the grids, uprights and spacing means in firm mutual engagement.

5. In a sheet pickling crate the combination of a base, spaced upright members attached to the base, a pair of upwardly extending spaced grids disposed adjacent said upright members, spacing means interposed between said grids, clinching means arranged to engage the grids to the uprights and to the base, and wedging means arranged to act on said grids to maintain the grids, uprights and spacing means in firm mutual engagement and to maintain the grids, base and spacing means in firm mutual engagement.

6. In a pickling crate the combination of a base, a plurality of mutually spaced grids extending upwardly from the base, spaced upright members attached to said base, a rod passing through said grids and said uprights and terminally formed to prevent retraction thereof, a rod passing through the grids and an aperture in the base and terminally formed to prevent retraction thereof, spacing members interposed between the grids and carried by said rods, and wedging means asso-

ciated with at least one grid to maintain the members in firm mutual engagement.

7. In a sheet pickling crate the combination of a base, upright members secured to said base, a spreader arranged to lie horizontally between said upright members and having therein seats for receiving said upright members, and retaining blocks cast and shrunk to the spreader and upright members in the regions of their mutual contact providing a jointless casing wholly covering the regions of mutual contact between the spreader and the uprights.

8. In a sheet pickling crate the combination of a base, upright members secured to said base, a spreader arranged to lie horizontally between said upright members and having therein seats for receiving said upright members, teats extending from the body of said spreader adjacent said seats, and retaining blocks cast and shrunk to the spreader upright members and teats in the regions of mutual contact of the upright members and the spreader providing a jointless casing wholly covering the regions of mutual contact between the spreader and the uprights.

In testimony whereof we have hereunto set our hands.

WILLIAM J. BRADDOCK.
